CLAIM

The ornamental design for a wireless Bluetooth headset, as shown and described.

DESCRIPTION

FIG. 1 is a perspective view of a wireless Bluetooth headset showing my new design;

FIG. 2 is a front view of the left piece of the wireless Bluetooth headset and a rear view of the right piece of the wireless Bluetooth headset;

FIG. 3 is a rear view of the left piece of the wireless Bluetooth headset and a front view of the right piece of the wireless Bluetooth headset;

FIG. 4 is a left side view of the wireless Bluetooth headset;

FIG. 5 is a right side view thereof;

FIG. 6 is a top view thereof; and,

FIG. 7 is a bottom view thereof.

The broken lines in the drawings depict portions of the wireless Bluetooth headset that form no part of the claimed design.
